ADJUSTING SCREW LOCK FOR ADJUSTABLE
END WRENCHES

Theodore F. Jackson, Rockford, Ill., assignor of
one-sixth to Roy M. Buck, Belvidere, one-sixth
to Donald E. Carlyle and one-sixth to Carl F.
Christensen, both of Rockford, Ill.

Application August 1, 1952, Serial No. 302,143

2 Claims. (Cl. 81—165)

1

This invention relates to a new and improved adjusting screw lock for an adjustable end wrench.

It is well known that adjustable end wrenches, commonly called "crescent" wrenches, have long been subject to the objection that the movable jaw will not hold its adjustment, and there is consequently the need for repeatedly correcting the adjustment, which is both time-consuming and very annoying. Various constructions have been devised in an effort to solve this problem, but, so far as I am aware, none has been adopted commercially, and it is my belief that this is because they have been too complicated and expensive in construction in relation to the advantages offered, and because they were not practical from the standpoints of dependability and positive action, and were not handy and speedy in operation in the un-locking and locking of the adjusting screw or worm when an adjustment has to be made. It is, therefore, the principal object of my invention to provide an adjustable end wrench which is designed to avoid so far as possible all of the objections mentioned and yet meet the various practical requirements enumerated.

The invention is illustrated in the accompanying drawings, in which—

Figs. 1 and 2 are side views, taken from the opposite sides, of an adjustable end wrench made in accordance with my invention, a portion of the handle being broken off in Fig. 1;

Figs. 3 and 4 are longitudinal sections on the broken line 3—3 of Fig. 1, showing the wrench with the adjusting screw locked in Fig. 3 and unlocked in Fig. 4, and

Fig. 5 is a fragmentary side elevational view like a portion of Fig. 2 but showing a modified or alternative construction.

Similar reference numerals are applied to corresponding parts throughout the views.

Referring mainly to Figs. 1 to 4, the reference numeral 6 designates the handle of an adjustable end wrench, on the enlarged outer end portion of which is defined a head provided with the usual fixed jaw 7 and associated movable jaw 8. The latter is slidably guided, as shown at 9, for adjustment transversely of the head and has rack teeth 10 along the inner edge meshing with the threads 11 of an adjusting screw 12 rotatably mounted on a pin 13 for manual operation in the usual way in a rectangular opening 14 provided in the head. The periphery of the threads 11 is usually knurled or roughened in some other way to provide a

good finger grip surface to facilitate manual operation. In accordance with my invention, the screw 12, which may be knurled on the periphery of its threads for a finger grip surface, has parallel grooves 15 cut in the threads in circumferentially spaced relation for locking engagement therein of a tooth 16 on the end of an elongated leaf spring 17 provided by the inwardly bent outer end portion of said spring. The spring 17 is disposed lengthwise of the handle and fastened at its inner end to the handle 6 by screws 18 and is normally bowed outwardly as appears in Fig. 3 and urges its toothed end 16 inwardly against the screw so as to engage in whichever groove 15 happens to be in register with the tooth, as shown in Fig. 3. Spring 17 is adapted to be flexed outwardly to the retracted position shown in Fig. 4 by means of a pin 19 that engages its inner side intermediate the ends thereof and is reciprocable in a hole 20 in the handle. A second elongated leaf spring 21 is disposed lengthwise of the handle on the opposite side from spring 17 and is fastened at one end to the handle by a screw 22 and normally projects outwardly in acute angle relationship to the handle 6 with its free end spaced from the pin 19, as shown in Fig. 3, but is adapted to be flexed inwardly against the handle, as shown in Fig. 4, to press pin 19 inwardly and flex the spring 17 outwardly to retracted position, so that the screw 12 can be turned to adjust jaw 8 in either direction. While spring 21 could conceivably be flexed inwardly by direct finger pressure, I prefer to provide for such operation a slide block or button 23 that is reciprocable in parallel guides 24 provided on the handle on opposite sides of the spring 21 by inwardly swedged flanges 25. The button 23 has a circular flange 26 of reduced thickness slidably freely in the guides in any position of rotation of the button, so that there is no danger of the button getting struck. The head of the screw 22 limits movement of the button 23 in one direction (see Fig. 3) and the end wall of the depression 27 in which the spring 21 and button 23 are disposed limits movement in the other direction. (See Fig. 4.)

If desired, a sheet metal plate 28 may be provided in lieu of flanges 25, as shown in Fig. 5, and be spot-welded to the handle 6', as indicated at 29. This plate provides a guideway between it and the handle 6' in depression 27 for the flange portion 26 of button 23, and the plate need only have an elongated slot 30 provided therein to receive the button and limit its travel. The operation with this construction is the same as

with the other construction, because the depression 27 is deep enough to allow sufficient outward flexing of spring 21 to permit spring 17 to effect locking engagement with screw 12.

In operation, the jaw 8 is adjusted by means of screw 12 while spring 17 is held retracted by spring 21 and button 23, as in Fig. 4, and, after the desired adjustment has been made, button 23 is moved back again, as in Fig. 3, to permit the tooth 16 on spring 17 to engage in whichever groove 15 is in register with the tooth. If the tooth happens to abut the screw between grooves it will snap into one the instant the screw turns a trifle one way or the other in response to thrust transmitted to the screw from the jaw 8, after which no further change in wrench adjustment can possibly occur accidentally, or by manual operation of screw 12, until the screw 12 is unlocked again.

It is believed the foregoing description conveys a good understanding of the objects and advantages of my invention. The appended claims have been drawn to cover all legitimate modifications and adaptations.

I claim:

1. An adjustable end wrench comprising an elongated handle having an enlarged end portion terminating in a fixed jaw and having an opening provided therein, an adjustable jaw provided with a rack portion slidably mounted on said end portion, a screw rotatably mounted in said opening and meshing with said rack, an elongated flat leaf spring disposed lengthwise of one side of said handle and fixed at one end to the handle and having the other end flexed outwardly but urged inwardly under inherent spring tension and having an inwardly bent edge portion on the extremity defining a tooth portion parallel to the axis of said screw and resiliently engaging the threads on said screw to pre-

vent rotation thereof, another elongated flat leaf spring disposed lengthwise of the other side of said handle and fixed at one end to the handle, the latter spring being bent intermediate its ends so that its free end projects normally away from the handle at an acute angle with respect to it, and a pin slidably in a hole provided in said handle engaging at its one end the free end portion of the second named leaf spring and at its other end a portion of the first named leaf spring intermediate the ends thereof, the second named leaf spring being adapted to be flexed inwardly toward the handle to cause the pin to flex the first named leaf spring outwardly away from said handle to a retracted position relative to said screw.

2. A wrench as set forth in claim 1, including a manually operable slider guided on said handle for movement lengthwise relative to said second named leaf spring and adapted to flex the outwardly bent free end portion of the latter inwardly toward the handle whereby to move said pin and flex the toothed free end portion of the first named leaf spring outwardly away from the handle to retracted position with respect to said screw.
